UNITED STATES PATENT OFFICE.

HROLF VON DEWITZ, OF NEW YORK, N. Y.

DESIGN FOR AN AUTOMOBILE-BODY.

50,115.

Specification for Design.

Patented Dec. 26, 1916.

Application filed September 9, 1916. Serial No. 119,316. Term of patent 3½ years.

To all whom it may concern:

Be it known that I, HROLF VON DEWITZ, a subject of the King of Denmark, and a resident of New York city, in the county and State of New York, have invented a certain new, original, and ornamental Design for Automobile-Bodies, of which the following is a specification.

The accompanying drawings show in Figure 1, a side elevation of an automobile, and Fig. 2 shows a plan view of an automobile body,—in which the top profile at A is substantially horizontal from the front as shown, C is a sheer or sloping portion of the top of the body extending rearward and downward from its junction with the profile at A, while C' is a substantially flat rear

deck. At B the upper edge of a wall or rail is substantially horizontal above the level of the profile at A, and extending, as shown, throughout the middle of the body, on the upper side, above the level of the sheer portion C.

I claim—

The ornamental design for an automobile body, as shown and described in the annexed specification.

Signed at New York, this 30th day of August, 1916.

HROLF VON DEWITZ.

Witnesses:

H. MUCHURNE,
HERMANN F. ARNTZ.
